David Edwards.

United States Patent Office.

DAVID EDWARDS, OF NEW YORK, N. Y.

Letters Patent No. 76,424, dated April 7, 1868.

IMPROVED CAR-REPLACER.

The Schedule referred to in these Letters Patent and making part of the same.

TO ALL WHOM IT MAY CONCERN:

Be it known that I, DAVID EDWARDS, of the city, county, and State of New York, have invented a certain new and useful Improvement for Putting Street and other Railroad-Cars on their Tracks, of which the following is a full, clear, and exact description, reference being had to the accompanying drawing forming part of this specification, and in which—

Figure 1 represents a side elevation of a street-car on a line or track of rails, with my improvement shown in section at one end applied thereto, and

Figure 2 an end elevation of the same, with my improvement also in section, or partly so.

Like letters indicate like parts in both figures.

In the case of a car or cars running off the track, as is so common or frequent an occurrence on street and other railroads, it has usually or heretofore been a matter of much labor and no little difficulty, accompanied by great loss of time, to replace them on the track.

The object of my invention is to obviate this difficulty, and the nature of my invention consists in arranging at either or both ends of the car, a wheel or roller, having its axis transverse to that of the running-wheels of the car, and made capable of being raised or lowered, so that when the car is on the track, it is free from contact with the ground, but when the car is off the track, it takes its bearing on the ground, and, lifting the end of the car, permits of an easy lateral swing or movement of the car back or to the track.

Referring to the accompanying drawing, A represents the body of a street-car; B B its running-wheels, and C C the front and rear platforms of the same. Either or both of these platforms I provide with a case or frame, D, in a line, which is intermediate and preferably central to the running-wheels, the same carrying a vertical screw, E, furnished with a crank or operating-wheel, F, and serving, accordingly as it is rotated in one direction or the other, to raise or lower a screw-box, G, to which the case D may act as a guide. Instead of the screw and screw-box G, other mechanical appliances answering as equivalents may be used. The lower end of the screw-box is made to carry a roller or wheel, H, or other suitable rest, so that when the screw-box is sufficiently depressed, it will, by its bearing on the way between the rails of the track, raise the end of the car to the necessary height, for, by swinging the car laterally, replacing its running-wheels when off the track, on the rails. I prefer, however, that this rest should be a roller or wheel, H, with its axis arranged transversely, or thereabouts, to that of the running-wheels, to facilitate the rolling or running of the end of the car laterally to bring its running-wheels over the track, when the screw E may be worked to lower the running-wheels on to the rails, and raise the wheel H free from all contact with the ground, or ordinary obstacles lying thereon, as represented by black lines in fig. 2, the lowered condition of said roller or wheel being shown by red lines in the same figure. By these means may a car be rapidly and easily replaced on the track.

What I claim as my invention, and desire to secure by Letters Patent, is—

1. The combination, with the car, at or near either or both of its ends, of a transverse intermediate ground-rest or bearing, capable of being raised or lowered, substantially as and for the purpose specified.
2. The combination, with a street or other railroad-car, of the screw E, screw-box G, and wheel or roller H, the latter having its axis arranged transversely, or thereabouts, to that of the running-wheels, also intermediate of the same, and capable of being raised or lowered, essentially as herein set forth.

DAVID EDWARDS.
